CLAIM

The ornamental design for a D-ring with multiple openings as shown and described.

DESCRIPTION

FIG. 1 is a perspective view illustrating a D-ring with multiple openings;

FIG. 2 is a top view thereof;

FIG. 3 is a bottom view thereof;

FIG. 4 is a side view thereof;

FIG. 5 is another side view thereof;

FIG. 6 is a front view thereof; and,

FIG. 7 is a back view thereof.

1 Claim, 7 Drawing Sheets(56)
